HAROLD A. WHEELER, OF GREAT NECK, NEW YORK, ASSIGNOR TO HAZELTINE CORPORATION, A CORPORATION OF DELAWARE

PUSH-PULL AMPLIFIER

Application filed July 16, 1929, Serial No. 378,630, and in Canada June 26, 1930.

This invention relates to improvements in thermionic amplifiers of the low frequency type adapted principally for amplifying currents in the audio frequency range. More particularly, the invention is directed to improvements in thermionic amplifiers operating in so-called "push-pull" circuits.

An object of the invention is to provide an amplifier of the type mentioned which will furnish substantially distortionless amplification without the necessity for utilizing a biasing battery or an initial negative biasing potential on the control circuits or grids, of the thermionic tubes.

15 A further object is to provide an amplifier of the type specified adapted to furnish a high degree of substantially distortionless amplification.

20 A further object is to provide an amplifier of the type specified capable of delivering relatively large amounts of distortionless power output.

25 A further object is to provide an amplifier of the type specified wherein the signaling current delivered to the output circuit is caused to flow in series thru the plate circuits of a pair of tubes oppositely connected thereto, such arrangement permitting the most efficient delivery of distortionless power 30 to the output circuit.

A further object is to provide a meter in the amplifier circuit which gives a continuous indication of the signal intensity.

As a general proposition, one of the essential requisites to the distortionless amplification of the signaling currents by means of thermionic amplifiers consists in applying to the grids of the thermionic tubes a sufficiently large initial or permanent negative biasing potential to maintain them at all times negative relative to the corresponding cathodes or filaments. Otherwise, if the incoming signal wave has a sufficiently great peak value to carry the grid positive during 45 a portion of each cycle, space current will flow in the grid circuit during such portion thereby causing an increased voltage drop in the input circuit associated with the tube with resultant decrease in voltage impressed 50 between the grid and filament thereof as com-

pared to that of the corresponding negative portion of the signaling wave. As a consequence of this, the amplified signaling wave will contain a flattened portion during each interval that the grid is positive, which effect, 55 of course, is distortion.

It is possible by means of a well designed thermionic amplifier utilizing a sufficiently large permanent negative biasing potential on the grid, to obtain substantially distortionless amplification, but such a result is attained only by sacrificing certain other desirable features. In the first place, the use of the negative biasing potential on the grid of a tube increases the plate circuit impedance 65 thereof by a corresponding amount since the presence of the negative potential on the grid impedes the flow of electrons from the filament to the plate, thus requiring a higher plate circuit voltage for a given plate current. 70 The increased plate voltage required, together with the added grid bias voltage, involves an added expense to the amplifier construction.

In order to partially overcome the above 75 enumerated disadvantages accompanying the use of a permanent negative biasing potential on the grids of the tubes, the so-called "push-pull" amplifier circuit was developed. The push-pull amplifier, as frequently constructed, comprises in essence an input transformer having the secondary winding thereof connected between the respective grids of a pair of similar thermionic tubes, an output transformer having the primary winding 85 thereof connected respectively between the anodes of said tubes, and having the cathodes connected in common to the midpoint of the input transformer secondary winding and also thru a direct plate current supply source 90 to the midpoint of the output transformer primary winding.

If now a sine wave of signaling current is impressed upon the input transformer of such a push-pull amplifier, there will at each 95 instant of time be a signal voltage impressed in a positive sense between grid and filament of one tube and an equal signal voltage impressed in the negative sense between grid and filament of the other tube, and since the 100

voltages thus impressed produce additive effects in the output transformer secondary, it is thus insured that each positive half cycle of amplified signaling current will be identical in wave form with the corresponding negative half cycle. This, however, does not necessarily mean that the amplified wave will be distortionless; it merely means that the even harmonics of the fundamental frequency will be eliminated. The odd harmonics may still be present in sufficient magnitude to cause appreciable distortion.

In addition to the distortional effects noted with the push-pull amplifier as commonly constructed, any grid current in flowing thru the input transformer secondary winding will cause a considerable voltage drop therein which will reduce the net signaling voltage applied between the grid and filament of the tubes and in this way limit the amplification obtainable.

The amplifier of the present disclosure is adapted to overcome the objections pointed out above with reference to the push-pull amplifier as commonly constructed. To accomplish this the input transformer having the tapped secondary winding as commonly used in such amplifiers is replaced or supplemented by a pair of equal high impedance elements such as a pair of equal resistances, serially connected between the grids of the tubes. The midpoint between such elements is connected directly to the cathodes in common but is not connected to the midpoint of the transformer secondary winding. For proper operation the impedances must be large in magnitude as compared to the grid-to-cathode resistances of the tubes so that when a signaling voltage is impressed on either grid in a positive sense the cathode-to-grid resistance of the tube will effectively short circuit the corresponding impedance element.

If with the arrangement of elements as described, a signaling voltage wave is impressed between the grids of the tubes, nearly all of the voltage will at any instant exist across the tube having the more negative grid. The reason for this is that the more negative grid draws no grid current and hence presents substantially an open circuit connected across its impedance element. The tube whose grid terminal is positive at any instant offers a relatively low resistance to the flow of grid current, and thus substantially short-circuits the impedance connected thereacross. Inasmuch as the grid current at any instant flowing in this short-circuiting path must also flow through the impedance connected to the more negative grid, it is so limited thereby that the voltage distribution between tubes will be such that nearly the full voltage at each instant will be impressed across whichever tube has the more negative grid at that instant. The positive

grid becomes in effect an instantaneous connection directly between the transformer and the filaments.

The advantages of such a mode of operation are apparent. In the first place, neither grid can ever become highly positive and draw excessive grid current. Furthermore, the grid current can not in this case cause a voltage drop in the input circuit, thereby eliminating this distorting and power-limiting effect observed in common push-pull amplifiers.

The major portion of the signal voltage is impressed at each instant on the negative grid. Therefore, one tube amplifies the half waves of the one polarity whereas the other tube amplifies the other half waves. The full waves are then reproduced by recombining the amplified half waves in the output circuits.

As a result of this method of operation, it has been found that the ordinary means for connecting the push-pull amplifier to an output circuit, namely, thru an output transformer having the primary winding tapped at the midpoint and connected thru a "B" battery to the cathodes in common, does not permit the maximum power output from the present circuit. Due to the fact that only one tube at a time is "active", the output transformer in such case acts as a three-winding transformer having a single primary connected to the active plate and a pair of windings connected respectively to the "inactive" tube and to the output circuit. The dynamic plate circuit resistances of both tubes are thus connected effectively in parallel with the output circuit so that the inactive plate acts as a dissipative shunt across the output circuit.

It is well known that in the operation of thermionic tubes the maximum power output consistent with good operation is obtained when the load impedance is substantially greater than the plate resistance. In the above case, the effective load impedance of inactive plate and output circuit in parallel is always less than the active plate resistance.

In contrast with the above arrangement wherein the output circuit and plate circuit resistances are effectively in parallel, it is possible to so arrange the elements that the amplified signal current flows in series thru the active and inactive plate resistances and thru the output circuit. The above ideal condition can then be realized and nearly the entire output power from the active plate be delivered to the output circuit. A much smaller signal current now flows thru the inactive tube at any instant.

The series arrangement for the output circuit is obtained by replacing the commonly used output transformer having the tapped primary winding, with a pair of equal un-

coupled high impedances such as choke coils or resistances, which are serially connected between the plates of the tubes. The direct plate current supply is then connected between the filaments and a point intermediate the impedances. Only the steady direct plate current supply flows thru the high impedances. The major part of the signal current due to the choking action thereof is forced to flow in series thru the active and inactive tubes and thru the output circuit.

The series type of output circuit is inferior to the usual output transformer when applied to the common push-pull amplifier using a highly negative grid bias. The reason is that with such an amplifier both tubes are about equally active at each instant in delivering current to the output circuit, and the less active tube is the one with the higher instantaneous plate resistance.

The expressions "divided input section" and "divided output section" as used in the specification and claims denote the push-pull connection of the amplifier tubes in which the cathodes of the push-pull connected tubes are joined together and connected respectively to an intermediate point of the input circuit and output circuit, while the grids are connected to respective opposite outer terminals of the input circuit and the anodes are connected to opposite outer terminals of the output circuit.

Referring now to the drawings:

Fig. 1 shows in circuit diagram form a push-pull amplifier having the input section thereof arranged in accordance with the present invention and utilizing generalized impedance elements in the grid circuit. The output circuit is terminated in a standard manner by means of an output transformer having a tapped primary winding for connection to the filaments.

Fig. 2 shows an amplifier of the above type wherein both the input and output sections are arranged in accordance with the present invention utilizing generalized impedances therefor.

Fig. 3 shows a modification of Fig. 2 wherein generalized impedance elements and an input transformer are associated with the input circuit while the output circuit is terminated in choke coils and condensers suitably arranged.

In Fig. 4 each of the generalized impedance elements of Fig. 2 is replaced by a separate transformer. The operation, however, is the same as that of Fig. 2.

Fig. 5 shows two amplifier stages connected in cascade. The arrangement of each stage is in accordance with Fig. 1 with the exception that the second stage shows an auto-transformer and condensers in the output section.

Fig. 6 shows a two-stage amplifier in accordance with the invention wherein a spe-

cial type of loud speaker unit is connected directly in the output section of the second stage.

Like elements are designated in the same manner in each of the drawings.

Referring to Fig. 1, the amplifier comprises similar vacuum tubes V_1 and V_2 each having a grid G , filament or cathode F and plate P electrodes. The filaments F are heated in any suitable manner, not shown, and are conductively connected as shown by lead 4. Between the grids of tubes V_1 and V_2 are serially connected the similar and electrically distinct impedance elements Z_1 and Z_2 . These impedance elements are shown in generalized form indicating that any suitable type of high impedance may be used such as resistances or choke coils. Preferably, resistances should be used for this purpose having a value of .1 to 1.0 megohm dependent upon the characteristics of the particular tubes used.

The filaments F in common are conductively connected to the point 3 between elements Z_1 and Z_2 by means of lead 1. A milliammeter M is interposed in lead 1 for purposes of continuously indicating the power level of the signaling current. (In the usual grid-bias amplifier, the grid current meter does not indicate the signal intensity except when overloading.) The primary P_2 of an output transformer T_2 is connected between the plate electrodes P of tubes V_1 and V_2 . The midpoint of winding P_2 is connected in the usual manner thru a plate current supply source B to the filaments in common by means of lead 2. The secondary S_2 of transformer T_2 terminates in output terminals O to which an output impedance indicated by rectangle L may be connected as indicated by the dotted lines.

The input section comprises terminals I connected respectively to the grids of tubes V_1 and V_2 . The source of incoming signaling current, indicated by A , may be connected directly to terminals I or may be applied thereto thru an input transformer T_1 in the manner shown.

As the general operation of the amplifier of Fig. 1 has been explained above, only a few specific points need be noted here. At an instant when the applied signaling current is such that the lower terminal I is negative relative to the upper terminal I , the grid of tube V_2 will be negative and that of tube V_1 positive relative to the filaments. The impressed signaling current will flow, therefore, from the lower terminal I thru impedance Z_2 to point 3 where it will divide, a small portion flowing thru impedance Z_1 to the upper terminal I and the major portion thru lead 1 and milliammeter M ; and thence thru the space path from filament to grid of tube V_1 to the upper terminal I . Since the grid circuit of tube V_1 is of low impedance

relative to element Z_1 , the grid circuit practically short-circuits the element, so that substantially all of the voltage drop due to the impressed signal is across impedance Z_2 and hence across the grid circuit of the tube V_2 which being biased negatively thereby is practically an open circuit.

Thus during the interval that the lower terminal I is negative relative to the upper terminal, tube V_2 is active in delivering amplified signaling current to transformer T_2 . Tube V_1 , on the other hand, is relatively inactive but the small signaling current flowing in the plate circuit thereof produces an effect in transformer winding S_2 which aids the effect therein of the current flowing in the plate circuit of tube V_2 .

During the next half cycle, i. e., while the upper terminal I is negative relative to the lower terminal, the above conditions will be reversed, the grid of tube V_1 being negative and hence active while that of tube V_2 is positive and hence relatively inactive.

Where an input transformer T_1 is used, all of the current flowing in the secondary thereof must flow in series thru the high impedance Z_1 or Z_2 as the case may be which thus limits the current magnitude to a small value and hence prevents appreciable magnetic saturation of the transformer or appreciable impedance drop therein.

With the arrangement of Fig. 1, the plate circuits of tubes V_1 and V_2 are effectively in parallel with the output impedance L , with the resultant disadvantages pointed out above. In Fig. 2, on the other hand, these same elements are in series, due to the presence of the similar high impedance elements Z_3 and Z_4 serially connected between the plate electrodes respectively of tubes V_1 and V_2 . These impedances should be of the order of 10,000 ohms each and are either resistances, large choke coils, or magnetically distinct transformer windings. The battery lead 2 is connected to the midpoint between the impedances as shown so that the space current supply to the tubes V_1 and V_2 flows oppositely thru elements Z_3 and Z_4 , respectively.

The high impedance of elements Z_3 and Z_4 tends to maintain the current flowing therethru constant at its steady direct current value. When signals are being received, the reduction in space current in the active tube tends to decrease the current in the corresponding impedance by a like amount, but a small current change therein sets up a choking action which forces the major portion of the signaling current to flow in series thru the plate circuits of the active and inactive tubes and thence thru the load impedance L with the resultant advantages pointed out above.

Assuming the active tube capable of delivering a certain maximum current value

without appreciable distortion, the maximum energy will be delivered to the impedance L when its magnitude is large compared to the dynamic plate circuit resistance of the tube. Since, however, the impedances Z_3 and Z_4 must be large compared to L , this would mean a corresponding increase of the same with resultant added resistance in the battery supply path which would in turn call for an increased battery "B" and would at the same time introduce certain other undesirable features well known in tube operation. It has been found theoretically and in practice that the optimum arrangement is obtained when the impedance L is about four times the dynamic plate circuit resistance of a single tube. On the same basis, with the arrangement of Fig. 1, the impedance L should also be about four times the dynamic resistance of a single tube, if the total primary and secondary turns are equal in number.

Fig. 3 shows an arrangement identical in operation with Fig. 2, but one wherein an input transformer T_1 is permanently associated with the input circuit and wherein the generalized impedance elements Z_3 and Z_4 are specified to be similar choke coils L_1 and L_2 . The capacities C are inserted in the output leads O to keep the direct plate voltage off the output circuit.

Fig. 4 shows an arrangement similar electrically with Fig. 2, but one wherein the generalized impedance elements Z_1 to Z_4 , inclusive, are specified to be separate transformers T_3 to T_6 , inclusive. The primaries of transformers T_3 and T_4 are serially connected between the input terminals I , and the secondaries thereof serially connected between the grids. The midpoint between the secondaries is connected to the filaments by means of lead 1. A corresponding arrangement is shown for the output transformers T_5 and T_6 . It should be pointed out that each of transformers T_3 to T_6 , inclusive, operates independently since each is on a separate magnetic core. In this respect the operation differs essentially and advantageously from that of transformer T_2 of Fig. 1, in which all windings are magnetically coupled.

Fig. 5 shows a two-stage amplifier with tubes V_1 and V_2 comprising the first stage and tubes V_3 and V_4 comprising the second stage. The output of the first stage and the input of the second stage are similar in arrangement to Fig. 1, while the output of the second stage utilizes an auto-transformer or tapped choke coil T_2 and is thus similar electrically to the output of the first stage.

Fig. 6 shows a two stage amplifier utilizing a transformer T_1 and equal resistance elements R_1 and R_2 for input of the first stage, and resistances R_3 and R_4 for the output thereof. The successive stages are intercon-

nected by transformer T_2 , with the input to the second stage utilizing equal generalized impedance elements Z_1 and Z_2 , usually resistances.

5 The output circuit of the amplifier comprises the two coils 5 and 6 of special type of loud speaker known as a "Farrand inductor dynamic" speaker. This speaker which is especially adapted for use with 10 the type of amplifier disclosed herein, comprises the cone-shaped acoustical diaphragm 7, a permanent magnet 8 having affixed to poles thereof two opposed U-shaped pole pieces 9 and 10.

15 The pole pieces are so dimensioned as to leave an air gap between the opposite legs thereof, in which space the armature 11 is suspended in such manner as to be free to vibrate only along the line of the diaphragm 20 connecting rod 12, so that the cone 7 will be vibrated in accordance with the oscillations of the armature.

The coil 5 is placed about the upper leg of the pole piece 10, and the corresponding 25 coil 6 about the lower leg of pole piece 9. Coil 5 is connected directly in the plate circuit of tube V_3 , and coil 6 in the plate circuit of tube V_4 in such manner that the flux set up by the direct space current in each 30 case aids the flux of the permanent magnet 8.

The armature 11 has a length about equal to the distance between centers of the legs of the pole pieces 9 and 10, and being positioned 35 symmetrically in the air gap is thus pulled equally in opposite directions by the steady fluxes in the two gaps, respectively, between the pole pieces.

If now a signal wave be impressed upon 40 the input terminals of the amplifier, the action of the amplifier is such that the current in signal coil 5 decreases when the grid of tube V_3 is negative, and at the same time the current in signal coil 6 remains constant 45 at the normal direct current value or increases very little because the grid of tube V_4 is positive. Likewise, when the grid of tube V_3 is positive, the current in signal coil 5 is practically at the normal direct current 50 value and the current in signal coil 6 is decreased. From the foregoing, it is seen that the signal coils are alternately operative, and furthermore, the coil which is inoperative 55 exerts no influence upon the coil which is operative. This gives the result that the inactive tube of low plate resistance is not effective a shunt across the output of the active tube, as would be true if a single output transformer were utilized.

60 The principal advantage of connecting the loud speaker directly in the output circuit is that all frequencies operate on the speaker unit to equal advantage, whereas if the speaker were connected to the output terminals of 65 an amplifier using matched choke coils as in

Fig. 3, the choke coils would offer a relatively small impedance to the lower signaling frequencies and hence would shunt a considerable portion thereof away from the speaker unit. Another advantage of Fig. 6 lies in 70 the elimination of the high impedance elements in the output circuit, their places being taken by coils 5 and 6 of the speaker unit. This, of course, represents an economical advantage. The greatest distortionless power 75 output is secured when coils 5 and 6 are practically without magnetic coupling and when the effective impedance of each coil is approximately three times the output impedance of the tube connected thereto. 80

I claim:

1. An electric wave repeating apparatus comprising divided input and divided output sections with a pair of electron discharge devices each including a control electrode 85 connected in opposition therebetween, and high impedance means associated with said input section adapted to cause a signal wave applied between said control electrodes to be repeated at each instant in substantial entirety by the said device which receives a negative potential therefrom. 90

2. An electric wave repeating apparatus comprising divided input and divided output sections with a pair of electron discharge devices each including a control electrode connected in opposition therebetween and high resistance means directly associated with the input sections of said devices adapted to cause a signal wave applied between said control 95 electrodes to be impressed in substantial entirety at each instant upon the said device which receives a negative potential therefrom, whereby one device repeats the positive portions and the other device the negative portions of said signal wave. 100

3. An electric wave repeating apparatus comprising divided input and divided output sections with a pair of electron discharge devices each including a control electrode connected in opposition therebetween, and electrically uncoupled high impedance means individually respectively to said divided input sections adapted to cause a signal wave applied between said control electrodes to be impressed in substantial entirety at each instant upon the said device which receives a negative potential therefrom whereby the latter said device repeats the signal. 110

4. An electric wave repeating apparatus comprising divided input and divided output sections with a pair of electron discharge devices connected in opposition therebetween, high impedance means associated with said input section adapted to cause a signal wave applied to said input section to be impressed in substantial entirety at each instant upon the said device which receives a negative potential therefrom, whereby said latter device repeats the signal, and additional high im- 120
125
130

pedance means associated with said output section adapted to cause the repeated wave to flow in series thru the space paths of both said devices.

5. An electric wave repeating apparatus comprising divided input and divided output sections with a pair of electron discharge devices connected in opposition therebetween, high impedance means associated with said 10 input section adapted to cause a signal wave applied to said input section to be impressed in substantial entirety at each instant upon the said device which receives a negative potential therefrom, whereby said latter device 15 repeats the signal, and additional high impedance means interposed in the space current supply paths of said devices adapted to cause the repeated wave to flow serially thru the space paths of both said devices.
20. An electric wave repeating apparatus comprising divided input and divided output sections with a pair of electron discharge devices connected in opposition therebetween, high resistance means associated with said 25 input section adapted to cause a signal wave applied to said input section to be impressed in substantial entirety at each instant upon the said device which receives a negative potential therefrom, whereby said latter device 30 repeats the signal, and high impedance means individual to the respective divided portions of said output section adapted to cause the repeated wave to flow serially thru the space paths of both said devices and thru 35 said output section.

7. An electric wave repeating apparatus comprising divided input and divided output sections with a pair of electron discharge devices connected in opposition therebetween, 40 high impedance means individual to the said divisions to said input section adapted to cause a signal wave applied to said input section to be impressed in substantial entirety at each instant upon the said device which receives a negative potential therefrom, whereby said latter device 45 repeats the signal, and additional high impedance means individual to the respective divided portions of said output section and adapted to cause the repeated 50 wave to flow serially thru space paths of both said devices and thru said output section.

8. Thermionic electric wave repeating apparatus for providing high degrees of substantially distortionless amplification in the 55 absence of negative biasing potentials in the control circuits of the thermionic elements, comprising a pair of electron discharge devices connected in opposition to an output section, each said device including anode, 60 cathode and a control electrode, a pair of uncoupled high impedance elements serially connected directly between said control electrodes, a connection from said cathodes to a point between said impedances, and an 65 input section connected to said control elec-

trodes, said high impedance elements being adapted to cause a signal wave applied to said input section to be impressed in substantial entirety upon the device which received a negative potential therefrom, whereby said latter device alone repeats the signal. 70

9. Thermionic electric wave repeating apparatus for providing high degrees of substantially distortionless amplification in the absence of negative biasing potentials in the control circuits of the thermionic elements, comprising in combination, a pair of electron discharge devices connected in opposition to an output section, each said device including anode, cathode and a control electrode, high 75 resistance means connected directly between said control electrodes having an intermediate point thereof connected to said cathodes, and an input section having its opposite terminals connected respectively to said control 80 electrodes, said high resistance means being adapted to cause a signal wave applied to said input section to be impressed in substantial 85 entirety upon the device which receives a negative potential therefrom, whereby said latter device repeats the signal. 90

10. Thermionic electric wave repeating apparatus for providing high degrees of substantially distortionless amplification in the absence of negative biasing potentials in the control circuits of the thermionic elements, comprising a pair of electron discharge devices connected in opposition to an output section, each said device including anode, cathode and a grid electrode, a pair of uncoupled fixed impedance elements of large magnitude relative to the lowest grid-cathode 95 resistance of said devices during operation serially connected between said grids, a connection from said cathodes to the point between said impedances, and an input section connected to said grids, said impedance elements being adapted to cause a signal wave applied to said input section to be impressed in substantial entirety upon the device which receives a negative potential therefrom, whereby said latter device repeats the signal. 100

11. Thermionic electric wave repeating apparatus for providing high degrees of substantially distortionless amplification in the absence of negative biasing potentials in the control circuits of the thermionic elements, comprising a pair of vacuum tubes each having grid, cathode and anode, means connecting said tubes in opposition to an output section, a pair of equal fixed resistance elements of large magnitude relative to the lowest grid-filament resistances of said tubes in operation, said resistance elements being serially connected directly between said grids, a connection from said cathodes to the point between said resistances, and an input section connected to said grids, said resistance elements being adapted to cause a signal wave applied to said input section to be repeated 115 120 125 130

in substantial entirety by the tube which receives a negative potential therefrom, whereby said latter tube repeats the signal.

12. Thermionic electric wave repeating apparatus for providing high degrees of substantially distortionless amplification in the absence of negative biasing potentials in the control circuits of the thermionic elements, comprising in combination a pair of vacuum tubes each including anode, cathode and grid electrodes, a pair of impedances serially connected directly between said grids with the point between said impedances connected to said cathodes, said impedances being adapted to prevent the flow of excessive current in the grid circuits of said tubes when large signal voltages are applied between said grids, and also being adapted to cause said voltages to be impressed in substantial entirety upon the tube which receives a negative potential therefrom, whereby said latter tube repeats the signal.

13. Thermionic electric wave repeating apparatus for providing high degrees of substantially distortionless amplification in the absence of negative biasing potentials in the control circuits of the thermionic elements, comprising in combination a pair of vacuum tubes each including anode, cathode and grid electrodes, resistance means connected directly between said grids, said means being connected at an intermediate point thereof to said cathodes and adapted substantially to suppress the flow of space current in the grid circuits of said tubes for voltages impressed between said grids, and also being adapted to cause said voltages to be applied in substantial entirety upon the tube which receives a negative potential therefrom, whereby said latter tube repeats the signal.

14. Thermionic electric wave repeating apparatus for providing high degrees of substantially distortionless amplification in the absence of negative biasing potentials in the control circuits of the thermionic elements, comprising a pair of electron discharge devices, each including anode, cathode and grid, connected in opposition to an output section, an input section comprising a pair of uncoupled high impedance elements serially connected between said grids with the point between said elements connected to said cathodes, whereby in operation a signal wave applied between said grids is repeated at each instant in substantial entirety by the said device which receives a negative potential therefrom.

15. Thermionic electric wave repeating apparatus for providing high degrees of substantially distortionless amplification in the absence of negative biasing potentials in the control circuits of the thermionic elements, comprising a pair of electron discharge devices, each including anode, cathode and grid, connected in opposition to an output section,

and an input section comprising a pair of uncoupled high impedance elements serially connected between said grids with the point between said elements connected to said cathodes, whereby, in operation, a signal wave applied between said grids is at each instant impressed on the said device which receives a negative potential therefrom for causing said latter device to repeat said signal.

16. Thermionic electric wave repeating apparatus for providing high degrees of substantially distortionless amplification in the absence of negative biasing potentials in the control circuits of the thermionic elements, comprising a pair of vacuum tubes each having grid, cathode and anode, a pair of electrically distinct high impedance elements serially connected between said anodes with the point between said impedance elements connected to said cathodes, means for supplying space current to said tubes thru said high impedance elements respectively, a second pair of electrically distinct high impedances serially connected between said grids with the point between said second pair of impedances connected to said cathodes, an input section connected to said grids, said second high impedances being adapted to cause a signal wave applied to said input section to be impressed in substantial entirety upon the tube which receives a negative potential therefrom, whereby said latter tube repeats the signal, and an output section connected only to said anodes whereby the repeated signal follows in series through said output section and the anode-cathode space paths of said tubes, so that the low impedance space path of the tube having the momentarily positive grid is in series with the output section.

17. Thermionic electric wave repeating apparatus for providing high degrees of substantially distortionless amplification in the absence of negative biasing potentials in the control circuits of the thermionic elements, comprising a pair of vacuum tubes each having cathode, anode and grid, high resistance means connected between said grids tapped at an intermediate point to said cathodes, a pair of choke coils serially connected between said anodes, a space current supply source connected from said cathodes to a point between said choke coils, an input section connected to said grids, said high resistance means being adapted to cause a signal wave applied to said input section to be impressed in substantial entirety upon the tube which receives a negative potential therefrom, whereby said latter tube alone repeats the signal and an output section connected only to said anodes whereby the repeated signal flows in series through said output section and through the anode-cathode space paths of said tubes, so that the low impedance space

path of the tube having the momentarily positive grid is in series with said output section.

18. An electric wave repeating apparatus comprising a pair of vacuum tubes each having cathode, anode and grid, a pair of impedance elements of large magnitude relative to the lowest grid-filament resistance of said tubes in operation serially connected between said grids, a connection from the point between said impedances to said cathodes, a second pair of high impedance elements serially connected between said anodes, a connection from the point between said second pair of impedances to said cathodes thru a space supply source, and input and output sections connected to said grids and to said anodes respectively, said impedance elements connected between said grids being adapted to cause a signal wave applied to said input section to be impressed in substantial entirety upon the tube which receives a negative potential therefrom, whereby said latter tube alone repeats the signal, and said repeated signal flows in series through said output sections and through the anode-cathode space paths of said tubes so that the low impedance space path of the tube having the momentarily positive grid is in series with said output section.
19. An electric wave repeating apparatus in accordance with claim 7 wherein the effective impedance of said output section is substantially four times the output impedance of either said electron discharge device.
20. An electric wave repeating apparatus comprising a pair of electron discharge devices connected in opposition between input and output sections, each said device including anode, cathode and control electrodes, an input transformer having a secondary winding connected between said control electrodes respectively and having a point thereof connected thru high impedance means to said cathodes, whereby said secondary winding is normally maintained at substantially the potential of said cathodes, said high impedance means comprising a pair of noninductively related impedance elements, one of which is connected between one of said control electrodes and said cathodes and the other of which is connected between the other of said control electrodes and said cathodes, whereby a signal wave present in said secondary winding is impressed at each instant in substantial entirety upon the device whose control electrode receives a negative potential therefrom, so that said latter device repeats the signal.

21. An electric wave repeating apparatus comprising a pair of electron discharge devices connected in opposition between input and output sections, each said device including anode, cathode and control electrodes, an input transformer having a secondary winding connected between said control electrodes

respectively, and having a point thereof connected thru high resistance means to said cathodes, whereby in the absence of signaling waves said secondary winding is maintained substantially at the potential of said cathodes, said high resistance means comprising a resistance connected between the control electrode and the cathode of each tube, whereby a signal wave present in said input transformer is impressed at each instant in substantial entirety upon the device whose control electrode receives a negative potential therefrom, whereby said latter device repeats the signal.

22. An electric wave repeating apparatus comprising a pair of electron discharge devices connected in opposition between input and output sections, each said device including anode, cathode and control electrodes, an input section connected between said control electrodes and having a point thereon connected thru a high impedance to said cathodes whereby in the absence of signal waves said input section is maintained substantially at the potential of said cathodes, said high impedance comprising non-inductively related impedance elements connected between the control electrode and the cathode of each discharge device, whereby a signal wave present in said input section is impressed in substantial entirety upon the device whose control electrode receives a negative potential therefrom, whereby said latter device is effective to repeat the signal.

23. An electric wave repeating apparatus comprising a pair of electron discharge devices connected in opposition to an output section, each said device including anode, cathode and control electrodes, an input section connected between said control electrodes and having the opposite terminals thereof connected thru high impedance means and a current indicating device in series to said cathodes whereby in the absence of signaling waves said input section is maintained substantially at the potential of said cathodes, and whereby the direct grid current indication upon said device is proportional to the signal wave intensity at all times, said high impedance means comprising a pair of non-inductively related impedance elements one of which is connected between the control electrode and cathode of each electron discharge device, whereby a signal wave applied at said input section is repeated at each instant in substantial entirety by the device which receives a negative potential therefrom.

24. In an electric wave repeating apparatus the combination of a pair of vacuum tubes each including cathode and grid electrodes, an input transformer having a secondary winding connected between said grids respectively, and a high impedance connecting a point on said secondary winding with said cathodes, whereby in the absence of sig-

naling waves said secondary winding is maintained at substantially the potential of said cathodes, and during reception of signaling waves of relatively large amplitude 5 excessive current is prevented from flowing in the grid circuits of said tubes, said high impedance being connected between each of said grid electrodes and the cathodes and being adapted to cause a signal wave applied 10 to said input transformer to be repeated at each instant in substantial entirety by the tube whose grid receives a negative potential therefrom.

25. In an electric wave repeating apparatus 15 for providing a high degree of substantially distortionless amplification in the absence of a negative biasing potential in the control circuits of said apparatus the combination of a pair of vacuum tubes each including cathode and grid electrodes, an input transformer having a secondary winding connected between said grids respectively, and high resistance means connecting the opposite terminals of said secondary winding 20 with said cathodes, whereby in the absence of signaling waves said secondary winding is maintained substantially at the potential of said cathodes and during reception of signaling waves of relatively large amplitude 25 excessive current is prevented from flowing in the grid circuits of said tubes, said high resistance means being adapted to cause a signal wave applied to said input transformer to be repeated at each instant in substantial 30 entirety by the tube whose grid receives a negative potential therefrom.

35. An electric wave repeating apparatus 30 for providing a high degree of substantially distortionless amplification in the absence of a negative biasing potential in the control circuits of said apparatus comprising a pair of vacuum tubes each having grid, cathode and anode, an output transformer having a primary winding connected between said anodes and having a point thereon connected to said cathodes thru high impedance and space current supply means in series, and an input transformer having a secondary winding connected between said grids respectively, 40 and having a point thereon connected to said cathodes thru high impedance means, whereby in the absence of signaling waves said secondary winding is maintained substantially at the potential of said cathodes, said 45 high impedance means being adapted to cause a signal wave applied to said input transformer in substantial entirety by the tube whose grid momentarily receives a negative potential therefrom.

50. 27. An electric wave repeating apparatus comprising a pair of vacuum tubes each having grid, cathode and anode, an output transformer having a primary winding connected between said anodes respectively, and having a point thereon connected to said cath-

odes thru high resistance and a space current supply means in series, and an input transformer having a secondary winding connected between said grids respectively, and having a point thereon connected to said cathodes thru high resistance means, whereby in the absence of signaling waves said secondary winding is maintained substantially at the potential of said cathodes, said high resistance means being adapted to cause a signal wave applied to said input transformer to be repeated in said output transformer at each instant in substantial entirety by the tube whose grid receives a negative potential therefrom.

28. An electric wave repeating apparatus comprising a pair of vacuum tubes each having grid, cathode and anode, an output section connected between said anodes and having a point thereon connected to said cathodes thru high impedance and a space current supply means in series, and an input section connected between said grids respectively, and having a point thereon connected to said cathodes thru high impedance means, whereby in the absence of signaling waves said input section is maintained substantially at the potential of said cathodes and whereby during signal reception the amplified signaling current is caused to flow 95 in series thru the anode circuits of both said tubes and said output section, said high impedance means being adapted to cause a signal wave applied to said input section to be repeated at each instant in substantial 100 entirety by the tube whose grid receives a negative potential therefrom.

29. An electric wave repeating apparatus in accordance with claim 28 wherein said output section has an effective impedance of 105 substantially four times the anode circuit impedance of either said tube.

30. An electric wave repeating apparatus in accordance with claim 2 wherein said divided output section comprises a pair of serially connected coils having associated therewith a movable armature so arranged that opposite current changes in said coils produce additive actuating forces upon said armature.

31. An electric wave repeating apparatus in accordance with claim 2 wherein said divided output section comprises a pair of serially connected coils having associated therewith a movable armature so arranged that opposite current changes in said coils produce additive actuating forces upon said armature, said coils having substantially zero magnetic coupling, and each coil having an effective impedance which is several 120 times the output impedance of the electron discharge device to which it is connected.

32. A distortionless thermionic amplifier comprising a pair of vacuum tubes each having anode, cathode and grid, an input trans-
